(57) **CLAIM**

We claim the ornamental design for a device for separately holding a plurality of golf clubs, as shown and described.

DESCRIPTION

FIG. 1 is a perspective view of a device for separately holding a plurality of golf clubs showing our new design; FIG. 2 is a front elevational view thereof;

FIG. 3 is a right side elevational view thereof, the left side elevational view being a mirror image thereof;

FIG. 4 is a top plan view thereof, the bottom plan view being identical thereto;

FIG. 5 is a rear elevational view thereof; and,

FIG. 6 is a reduced perspective view showing the device for separately holding a plurality of golf clubs in use; the phantom lines depict environmental structure for illustrative purposes only and form no part of the claimed design.
